(No Model.)

W. J. PTORNEY.
BLACKSMITH'S FORGE.

No. 406,767.

Patented July 9, 1889.

UNITED STATES PATENT OFFICE.

WILLIAM J. PTORNEY, OF McCACKEN, KANSAS.

BLACKSMITH'S FORGE.

SPECIFICATION forming part of Letters Patent No. 406,767, dated July 9, 1889.

Application filed March 29, 1889. Serial No. 305,305. (No model.)

To all whom it may concern:

Be it known that I, WILLIAM J. PTORNEY, a citizen of the United States, residing at McCracken, in the county of Rush and State 5 of Kansas, have invented a new and useful Tuyere for Blacksmiths' Forges, of which the following is a specification:

This invention relates to tuyeres for blacksmiths' forges, and it has for its object to provide a tuyere which shall prevent the spreading of the fire beyond the fire-pot, and which shall be capable of being used as a water-heating device for domestic purposes.

The invention further consists in the improved construction and arrangement of the cinder-box, and of the mechanism for raking the fire, and in the detailed construction and arrangement of parts, which will be herein-after described, and particularly pointed out 20 in the claims.

In the drawings, Figure 1 is a perspective view of my invention. Fig. 2 is a vertical transverse sectional view. Fig. 3 is a vertical section taken on the line $\alpha\alpha$ in Fig. 2. 25 Fig. 4 is a detail view of the slide at the bottom of the cinder-box.

The same letters refer to the same parts in all the figures.

A designates the tuyere, which consists of 30 a suitable box or casing, preferably circular in shape, and provided with a cover B, the upper side of which is concave, as shown at C, so as to form the fire-box of my improved forge. The under side of the concave cover 35 B has a downwardly-extending tubular shank D, the outer side of which may be screw-threaded, as shown at E, so as to engage the central screw-threaded opening F in the bottom of the casing A. The outer walls of the 40 latter are provided with vertical perforations G, registering with perforations A' in the top plate or cover B, to receive fastening-bolts I, by means of which the said cover may be permanently secured to the tuyere-box. 45 Packing of any suitable description may, when desired, be interposed between the upper edge of the box A and the projecting edge or flange of the cover B.

K designates a vertical rectangular shank, 50 which constitutes the cinder-box, and the upper end of which is provided with a horizontal flange L, through which the lower ends of

the fastening-bolts I are extended, so as to connect the tuyere to the said cinder-box. The latter is provided with a laterally-extending pipe M, which is to be connected in any suitable manner with a pair of bellows, or with a rotary blower of suitable construction. The lower end of the cinder-box is provided with a slide N, having a handle O, 60 and adapted to be retained in its closed position by means of a pivoted latch P. By removing the said slide the cinders accumulated in the cinder-box may be conveniently removed. The upper end of the cinder-box 65 communicates with the lower end of the pipe D, extending from the bottom of the fire-box; hence it will be seen that the blast of air entering the cinder-box through the pipe M is discharged directly in the center of the bottom of the fire-box. 70

Q designates a rotary grate, which is mounted in the tubular shank D. This grate is secured upon the upper end of a vertical rod R extending downwardly through the cinder-box, and having its bearings in suitable cross-bars S and in the bottom of the cinder-box. The lower end of the rod R is provided with a crank or handle T, by means of which it may be conveniently manipulated so as to 80 rake the fire, rake the cinders, and cause the latter to drop into the cinder-box, from which they may be afterward removed through the slide-door N.

The tuyere-box A is provided with a laterally-extending pipe U, which is connected by a flexible pipe V with a suitable tank or reservoir W, from which water may be supplied to the box A. The latter is also provided with a steam or blow-off cock X, and with a 90 valve or faucet Y, through which the hot water may be drawn out when desired for domestic purposes.

The operation of this invention and its advantages will be readily understood from the foregoing description, taken in connection with the drawings hereto annexed. The device is simple in construction and may be produced at a reasonable expense. The water in the tuyere completely surrounds the 95 fire-pot, thus preventing the latter from being overheated and the cinders or clinkers from adhering thereto. The air-blast from the cinder-box is directly upward through 100

the fire-box, and tends to keep the fire clear and bright. By the described arrangement of the cinder-box and the rotatable grate the fire-box may be quickly and easily cleaned, 5 and the accumulated cinders may be readily removed from the cinder-box.

Another important advantage of my invention is the facility with which hot water for domestic purposes may be at any time obtained.

Having thus described my invention, I claim—

1. In a blacksmith's forge, the combination, with the tuyere-box, the bottom of which has 15 a central screw-threaded opening, of the concavo-convex cover constituting the fire-pot and having a central downwardly-extending screw-threaded pipe, by which it is connected with the bottom of said box, substantially as 20 set forth.

2. The combination, with the annular water-chamber or tuyere and the top constituting the fire-pot, of the cinder-box located below the same and having the blast-pipe connected thereto, the rotatable grate located in 25 the central tube of the tuyere and having a rod extending downwardly through the cin-

der-box, and an operating-handle at the lower end of said rod, substantially as set forth.

3. The combination of the annular water-chamber or tuyere, the cinder-box located below the same, the rotatable grate, the removable slide at the lower end of the cinder-chamber, and the latch to retain said slide in position, substantially as and for the purpose 35 set forth.

4. The combination of the cinder-box having an annular horizontal flange at its inner end, the tuyere-box or water-chamber having perforations extending vertically through its 40 walls, the concave top plate constituting the fire-pot and having a central depending tube connecting it through the bottom of the water-chamber with the upper end of the cinder-box, and suitable connecting-bolts, substantially as and for the purpose set forth. 45

In testimony that I claim the foregoing as my own I have hereto affixed my signature in presence of two witnesses.

WILLIAM J. PTORNEY.

Witnesses:

S. E. HALL,
H. C. PTORNEY.

It is hereby certified that the name of the patentee in Letters Patent No. 406,767, granted July 9, 1889, for an improvement in "Blacksmith's Forges," was erroneously written and printed "William J. Ptorney," whereas said name should have been written and printed *William J. Ptomey*; and that the said Letters Patent should be read with this correction therein that the same may conform to the record of the case in the Patent Office.

Signed, countersigned, and sealed this 27th day of August, A. D. 1889.

[SEAL.]

GEO. CHANDLER,

Acting Secretary of the Interior.

Countersigned:

ROBERT J. FISHER,

Acting Commissioner of Patents.
